UNITED STATES PATENT OFFICE.

MICHAEL G. GRUNDMANN, OF FARIBAULT, MINNESOTA.

SHOE.

1,395,639.

Specification of Letters Patent.

Patented Nov. 1, 1921.

Application filed January 26, 1921. Serial No. 440,008.

To all whom it may concern:

Be it known that I, MICHAEL G. GRUNDMANN, a citizen of the United States, residing at Faribault, in the county of Rice and 5 State of Minnesota, have invented certain new and useful Improvements in Shoes, of which the following is a specification.

This invention relates to shoes and particularly to a method of making "turn 10 shoes".

The principal object of this invention is to provide a double sole equipped with a turn upper in order to cause the shoe to hold 15 its shape for a maximum period of time, at the same time giving the shoe the appearance of only a single sole.

The above and other objects of this invention will be in part described and in part understood from the following description 20 of the present preferred embodiment of the invention taken in connection with the accompanying drawings, wherein:

Figure 1, is a cross-sectional view of a shoe constructed in accordance with this invention.

Fig. 2, is a similar view showing the shoe before it has been turned and

Fig. 3, is a detail fragmentary sectional view illustrating to advantage the manner 30 of securing the upper to the soles of the shoe.

The invention consists especially of a main or outer sole 4, which is preferably provided with a chamfered marginal recess 5. An auxiliary or inner sole 6 is united to 35 the outer sole by means of nails, or stitches, in a manner well known in the art. After the soles have been united they are secured to the last pursuant to which the marginal edge of the inner sole is bent at right angles 40 and the marginal edge of a shoe upper 7, stitched or otherwise secured thereto. Following this, the said right angled margin of the inner sole is bent downwardly so as to clamp the marginal edge of the shoe upper 45 in the chamfered groove or recess 5. The shoe upper is then turned inside out in the manner shown in Fig. 1 of the drawings.

By making the shoe in the above described manner, not only will the shape of the shoe

be preserved, but the longevity of the shoe 50 will be greatly increased, especially in view of the fact that the outer sole can be replaced by the expenditure of a minimum amount of labor. For instance, when it is desired to replace the other sole, the stitches 55 or other means used for uniting the inner and outer soles are broken or removed which leaves the shoe upper secured only to the inner sole 6. A new sole can then be expeditiously secured to the inner sole in an appa- 60 rent manner.

It is apparent that various changes may be made in this device, especially in the manner of connecting the shoe upper to the shoe soles. However, the arrangement of the 65 double sole, their manner of connection, and the manner in which they are associated with the shoe upper are considered important factors of the invention. Moreover, the construction is simple and may be manufac- 70 tured at a minimum cost.

What is claimed is:

1. A method of making a turn shoe consisting in the use of inner and outer soles which are first secured together at a point 75 remote from their margins, the portion of the inner sole beyond its point of securement to the outer sole being then turned upwardly and sewed to the shoe upper, following which the latter is turned inside out to expose the said outer sole and incase the inner sole.

2. A method of making a turn shoe consisting in the use of inner and outer soles which are first secured together, next turning the marginal edge of the inner sole upwardly at right angles and securing the shoe upper thereto, then turning said right angled portion downwardly to clamp the shoe upper into engagement with the outer sole, 80 following which the said shoe upper is turned inside out.

In testimony whereof I affix my signature in presence of two witnesses.

MICHAEL G. GRUNDMANN.
